FOAM PACKAGING TRAY FOR FOOD

Donald K. Jewell, Naperville, Ill., assignor to
Restaurant Technology, Inc.

Filed Jan. 29, 1975, Ser. No. 544,871

Term of patent 14 years

Int. Cl. D9—03

U.S. CL. D9—219

FIG. 1

FIG. 2

FIG. 3

FIG. 4

FIG. 5

FIG. 6

FIG. 1 is a top plan view of a foam packaging tray for food showing my new design;

FIG. 2 is a bottom plan view;

FIG. 3 is a side elevational view, the opposite side being the same in appearance;

FIG. 4 is an elevational view looking from the right of FIG. 3, the opposite side being the same in appearance;

FIG. 5 is a top perspective view; and

FIG. 6 is a reduced scale exploded view in an open position.

I claim:

The ornamental design for a foam packaging tray for food, substantially as shown and described.
